Primary Examiner — Marcus Jackson

(57) **CLAIM**

The ornamental design for a solid state light assembly, as shown and described.

DESCRIPTION

FIG. 1 is a perspective view of the new design for a solid state light assembly having a transparent or semi-transparent optical guide for distributing light from solid state light sources, such as light emitting diodes, and an integrated internal thermal guide for dissipating heat from the solid state light sources;

FIG. 2 is an exploded perspective view thereof, showing the upper portion of the optical guide and the thermal guide removed from the other components of the assembly;

FIG. 3 is a side view thereof, the right view, left view, and rear view being mirror images of the side view shown;

FIG. 4 is a top view thereof; and,

FIG. 5 is a bottom view thereof.

The claim is directed to the collective appearance of the components of the solid state light assembly shown.

1 Claim, 4 Drawing Sheets
